CONTINUOUS WINDING APPARATUS

The present invention relates to an apparatus for automatically and electrically cutting wires, especially those of large diameter, in a high-speed continuous winding apparatus, particularly one having two or more spools for successive wire winding, in which wire is cut while being moved from a full spool to an empty spool.

Conventionally, when wires are made, it has been necessary to install an automatic and continuous wire winding apparatus for winding wires coming at a high speed from an extruding machine, a wire-drawing machine or a continuous annealer. And in order to wind the wire on the spools continuously from one spool to another, the winding apparatus is provided with an automatic cutting or shearing apparatus, which can cut the wires in a short time for switching the winding. Various methods and apparatus for automatic cutting or shearing have been developed and used in a high-speed continuous winding apparatus. However, almost all of these apparatus or methods are mechanical, so that a shock is often given upon cutting the wires, and especially, in case of cutting wires of a large diameter, a great shock is given to a winding apparatus and results in damage thereto. And also, it is very often that the operation of cutting becomes markedly unreliable and troublesome. Further, again, the conventional mechanical cutting apparatus or methods have such a defect that it is impossible to speed up cutting and to perform a highly efficient high-speed winding operation.

The present invention has for one of its objects to overcome such conventional defects as the above mentioned, and to provide an apparatus for automatic cutting by electricity, which is featured by consecutively winding wires on two or more spools continuously; and provides at least two electrodes, connected with a source of electricity, and installed between both of the spools. When the wire is wound on one spool and then shifted and wound on the other spool, the said travelling wire is contacted with at least two adjacent electrodes above mentioned at least on two close points of the said wire, the portion between the two points contacting with the electrodes being, in a short time, given electricity of high voltage or a large amount of current by the said source of electricity to generate a large amount of heat in the said portion. By the generated heat, the portion between the two points contacting with the electrodes is melted or heated to cut the wire. Thus, the apparatus according to the present invention eliminates shock during the cutting, and also, makes it possible to obtain a highly efficient continuous winding operation with high-speed wire cutting.

The apparatus for automatic wire cutting by electricity according to the present invention can be applied to, generally, (a) a continuous winding apparatus, in which two or more rotating shafts of spools are arranged coaxially to wind consecutively on spools; and (b) a continuous winding apparatus, in which rotating shafts of spools are arranged in parallel to wind the wire consecutively on spools. But, it is more preferable to apply the present invention to the latter-type arrangement.

An object of the present invention is to provide an apparatus, by which when a wire is shifted from a spool to another spool, the wire, especially the wire of a large diameter (for example, copper wire of more than 1.6 mm. in diameter) is cut electrically and automatically at a high speed between both of the spools without any shock.

The automatic wire cutting apparatus according to the present invention is such that in a continuous winding apparatus in which wire is wound consecutively on spools and a plurality of electrodes, connected with a source of electricity, are installed between two spools, whereby when the wire is wound on one spool and shifted to another spool, the shifting wire is contacted with the plural electrodes, subjected to momentary application of high voltage or large amount of current from the said source of electricity, and by a large amount of heat generating thereby melted or so softened between the points of contact as to be torn off by wire tension.

As the plurality of electrodes, two electrodes are installed for common use for the two spools, between two spools for common use for the two spools, so as to bring the wire into contact with the two electrodes when the wire is shifted from a spool to another spool, and vice versa. But, sometimes it is necessary to install a pair of electrodes for each spool.

In this case, when a prescribed amount of wire has been wound on a spool on one side, the said wire moves in the direction of an empty spool on another side to be wound thereon. At this moment, it often happens that the finishing end portion of the wire, wound on the former spool, is cut by one or both of the cutting apparatus, which is positioned respectively on the side of the spool on which the prescribed amount of wire has been wound, and on the side of the empty spool. Therefore, if the wire is cut by both the cutting apparatus and the cutting apparatus on the side of the spool on which the prescribed quantity of wire has been wound, the cut piece of the wire flies about, causing danger and damage to the wound wire.

Therefore, another object of the present invention is to eliminate such defects by installing a wire-cutting apparatus for each of two or more spools on which a wire is wound in succession, in such a manner that the cutting apparatus on the side of an empty spool is always in a position to cut the wire, while, the cutting apparatus on the side of the spool on which the wire is being wound, is out of the position to cut the wire.

According to the present invention both of the cutting apparatus are alternately worked to cut the wire at the right place, after it has been wound in a prescribed quantity. Thus, such a defect as occurrence of wire scrap as met in the conventional system can be eliminated.

A further object of the present invention is to provide a continuous winding apparatus in which a wire is wound consecutively on spools with the above-mentioned wire-cutting apparatus, having a barrel for winding the starting end portion of wire to be wound, an end plate having wire catchers on the circumferential fringe, and a barrel for winding the finishing end portion of wound-up wire with a cover on the periphery; all of said spools, barrels and end plates being installed in the said order on a driving shaft, on which the spool is supported, and also having an apparatus for winding up the starting end portion of wire to be wound on the former barrel, an apparatus for winding up the finishing end portion of wound-up wire on the latter barrel, a wire position adjusting guide for adjusting the position of wire so as to catch the wire on the wire catcher, and a traverser, which can also operate for moving the wire from the spool on which a prescribed quantity of wire has been wound toward the empty spool.

A still further object of the present invention is to provide an apparatus for ensuring proper travel of the wire to catch the wire on the wire catcher of the empty spool, when the wire is shifted to the said empty spool from the spool on which a prescribed quantity of wire has been wound.

When the wire is shifted and wound on the empty spool from the spool on which a prescribed quantity of wire has been wound, it is necessary that the wire be strained toward the empty spool by the traverser and the wire be caught on the wire catcher of the empty spool. But there is such a defect as that the wire can not be caught on the wire catcher on the side of the empty spool, because the track of the above-said strained wire changes considerably according to the quantity of wire on the side of the spool having already wound the wire and because the wire swings up and down owing to the large length of the wire between the traverser and the spool. In order to eliminate such fluctuations, it is necessary to make the contour of the wire catcher much larger than the outer diameter of the flange of the spool. But, as it is desirable to make the apparatus as small as possible, it is natural that the size of the wire catcher is limited. Therefore, it is quite difficult to catch the wire surely on a small wire catcher only, and it is often impossible to perform a perfect gripping.

In order to eliminate such defects in a continuous winding apparatus, a wire position adjusting guide, moving forward

and backward, is installed between the traverser and the spool, the said adjusting guide corrects the track of the wire from the spool on which a prescribed quantity of wire has been wound to the traverser which moves in the direction of the empty spool, and thus, the wire can be surely caught on the wire catcher on the side of the empty spool.

The present invention is, thus, characterized by the fact that the wire can be caught much more surely on the empty spool, regardless of the quantity of wire wound on the spool, and without any influence of the swing of the wire.

The wire position adjusting guide can be assembled with a catching guide, and it is possible to omit a pair of wire position adjusting guides which have been hitherto necessary, and also, cylinders for operation of the said adjusting guides. Further, the space between the spools can be smaller, and thus, the whole size of the apparatus may be compact and many advantages can thus be obtained.

A still further object of the present invention is to provide a continuous winding apparatus in which a wire is wound consecutively on spools supported on parallel rotating shafts, and a safety screen, serving also as a stopper, is installed between two spools, this screen being movable forward and backward in order to ensure a safe winding operation and to protect the apparatus.

The present invention provides a central safety screen for preventing a wire from swinging about at the time of cutting in a continuous winding apparatus.

The central safety screen according to the present invention is placed between two spools to intercept them, when one of the spools is winding the wire, and the screen is drawn backward so as not to interfere with the transfer of wire to be wound, when the wire is shifted from a full spool to an empty spool, and again, the screen comes forward between the two spools, after the wire has been transferred to be wound on the empty spool.

The central safety screen of the present invention serves also as a stopper (wire guide) for preventing the wire from engagement with a wire catcher of the empty spool, while the catching guide is coming to a prescribed position, when the screen is backward for the wire transfer.

Further screens may be, if necessary, installed on both sides of the traverser, according to the present invention, and when the wire is wound, either of these screens on both sides of the traverser is arranged in the same plane with the above central safety screen to ensure a safe operation and to protect the apparatus more perfectly at the time of wire winding.

Other objects of the present invention will be explained in the following examples. However, these examples are shown for better understanding of the present invention and, of course, do not limit the present invention.

Examples of the present invention shall be described referring to the attached drawings in which:

FIG. 1 illustrates the operation of a cutting apparatus according to the present invention;

FIG. 2 another example of FIG. 1;

FIG. 3, a circuit in the apparatus according to the embodiment of FIG. 1;

FIG. 4, an example of a shape of an electrode in the apparatus according to the embodiment of FIG. 1;

FIG. 5 shows a front view of a continuous winding apparatus, provided with a mechanism for pulling in or out the cutting apparatus according to the present invention;

FIG. 6, a plan view of the apparatus of FIG. 5;

FIG. 7 shows a front view of a continuous winding apparatus, provided with a spool according to the present invention;

FIG. 8, a plan view of FIG. 7;

FIG. 9 a side view of FIG. 7;

FIG. 10 a front view of a wire position adjusting guide;

FIG. 11 a plan of FIG. 10;

FIG. 12, a side view of the part for winding the starting end portion of wire to be wound and for catching the finishing end portion of wound up wire;

FIG. 13, an enlarged section of the part of FIG. 12;

FIG. 14 shows a front view of a continuous winding apparatus in order to illustrate the function of a wire position adjusting guide;

FIG. 15 shows a side view of FIG. 14;

FIG. 16 and FIG. 17 show respectively a front view and a side view of another example of a wire position adjusting guide;

FIG. 18 (a) and (b) show respectively a front view and a side view to illustrate the operation of the same;

FIG. 19 shows a side view of a catching guide, attached to a wire position adjusting guide;

FIG. 20 is a part of a front view of the catching guide of FIG. 19;

FIG. 21 shows a front view of a winding apparatus, provided with a safety screen according to the present invention; and FIG. 22 and FIG. 23 show respectively a section along A—A and a section along B—B of FIG. 21.

EXAMPLE 1: (FIG. 1 TO FIG. 4)

FIG. 1 illustrates the operation of the cutting apparatus of the present invention installed between two spools 1 and 2, supported on coaxial shafts revolving in the same direction. The respective spools 1 and 2 are provided with a suitable number of suitably shaped wire catchers 3 on the confronting outside surfaces of the flanges. The wire 5 is caught on the wire catchers 3 while travelling from the full spool 1, to the other empty spool 2. The travelling of the said wire 5 can be performed with the moving of the guide 4 to the position 4' on the right side, as shown with an arrow, by such a suitable known device as, for example, a microswitch. Then as the spools 1 and 2 are rotating in the same direction, shown with an arrow, the wire 5, caught on the said wire catchers, is rotated to contact with two electrodes 6 and 7 installed between the spools 1 and 2. The said electrodes 6 and 7 are fixed respectively to terminals *a* and *b* of a suitable source of electricity (not shown in the drawing) through springs or plate springs 8 and 9. If one of the electrodes 6 and 7 contacts with the wire 5, the electrode 6 is, just at the moment of said contact, pushed down by means of the spring 8, and then, the other electrode 7 will, at once, contact with the said wire 5. In this way, the two electrodes 6 and 7 are contacted almost simultaneously to short circuit the terminals *a* and *b*. By this

short circuit, a large amount of electric current flows between the terminals *a* and *b* through a direct current circuit from the source of electricity, for example, as shown in FIG. 3, and, consequently, a large amount of heat is generated instantly between the contact points, and the wire 5 is melted or heated and thus is cut.

FIG. 2 illustrates the operation of the cutting apparatus of the present invention, installed on two spools 1' and 2' supported on parallel rotating shafts revolving in different directions. The electrodes 6 and 7 are in a quite similar relation to the wire 5 as the embodiment shown in FIG. 1. Though the spools 1' and 2' rotate in different directions, the wire 5 is gripped and pulled downward by the wire catchers 3' of the spools 1' and 2'.

FIG. 3 shows an 2 of an electric circuit in the cutting apparatus of the present invention. *c*₁, *c*₂ and *c*₃ show condensers, which are always charged in the direct current circuit from the source of electricity to regulate the quantity of the current supplied between the terminals *a* and *b*, using the respective switches *S*₁ and *S*₂. *T* shows a transformer, on the secondary side of which a suitable number of terminals *t*₁, *t*₂, *t*₃, *t*₄....are attached to select a suitable voltage corresponding to the size and quality of the wire 5. The symbol *D* represents a diode and *S*₀ represents a contact of a relay. This contact *S*₀ controls the quantity of charge, accumulated in the condensers *c*₁....for a given time. When the condensers *c*₁....are short circuited the wire 5 is melted. The contact *S*₀ protects the transformer *T*, the rectifier and lines of the electric source from damages by the short circuit. The contact *S*₀ is disconnected before the condensers *c*₁....are discharged.

In the cutting apparatus of the present invention, it is possible to change the voltage and the capacity of the condensers c_1 , c_2 and c_3 , for example, in the above-mentioned electric circuit of FIG. 3, so that the wire 5 of any diameter can be instantaneously melted or heated to be easily cut.

In the cutting apparatus according to the present invention, the period of cutting can be made shorter. When R (resistance in a leading wire) of the time constant of RC is decreased, for example, in the circuit of FIG. 3, the wire 5 can be melted or heated to be easily cut in a time less than 100×10^{-6} seconds. For example, copper wires of 2.6 mm., 5.2 mm., 7.8 mm. or so in diameter can be melted or heated to be easily cut in a time of about one five-hundredth second. Therefore, the winding speed can be considerably increased as compared with the conventional mechanical method.

In the above-mentioned apparatus of the present invention, for example, cemented carbide may be used for the electrodes 6 and 7, and, as shown in FIG. 4, the end (10) of the electrodes may be edged. It is better to use two or more electrodes in case of a wire of a large diameter. The wire 5 can be contacted with the electrode 6 or 7, simultaneously or one after the other, by selecting suitably the space between the electrodes 6 and 7, or the level of installation. It is more desirable to make the wire contact with the electrodes one after the other than to make it contact the both electrodes simultaneously.

According to the present invention, as above mentioned, a wire, especially a wire of a large diameter can be cut without any shock and wound at considerably high speed.

EXAMPLE 2: (FIG. 5 AND FIG. 6)

11 shows a wire, which is wound on a spool 15 through a traverser 12 and a shifting guide 13'. When a prescribed quantity of the wire 11 has been wound on the spool 15, a detector (not shown in the drawing) is set in motion to dispatch a detection signal and an empty spool 15' starts to rotate at a prescribed speed of rotation. At the same time, a shifting base 22 for shifting guides moves horizontally by the revolution of an electric motor 14 and the shifting guide 13' stops at the position 13. The cutting apparatus 20' moves to the position 20' by means of a cylinder 21'. Receiving a stop signal from the shifting base 22 for shifting guides, a cylinder 19 is set in motion and a catching guide 18 travels from the position 18 to the position 18'. The wire 11 is caught on one wire catcher 17', attached to an end plate 16' adjacent to the spool 15', and then it is cut by the cutting apparatus 20'.

The end of the cut wire remains hanging on the wire catcher 17', and is wound, on the spool 15', as the said spool 15' rotates. The spool 15, on which a prescribed quantity of wire has been wound, comes to rest ready for replacement with another empty spool. The shifting base 22 for shifting guides 13, the catching guide 18' and the cutting apparatus 20' are restored respectively to a prescribed position. When a prescribed quantity of wire has been wound on the spool 15', the wire is wound newly on the empty spool 15, according to a similar operation to the above mentioned.

As above, according to the present invention, the wire cutting apparatus are installed respectively on the side of both spools 15 and 15'. The cutting apparatus are so made as to move forward and backward alternately, so that the wire is always cut only by the cutting apparatus on the side of the empty spool. In the conventional method, the two cutting apparatus for both the spools or the one for the spool on which a prescribed quantity of wire has been wound tends to produce scraps of wire. The scrap wires scatter thereby damaging the wire wound on the spool, or doing other harm, whereas, according to the present invention, the wire can be cut effectively without such damages or harms.

EXAMPLE 3: (FIG. 7 TO FIG. 13)

31, 31' show the spools for winding of the wire 32, and the spools 31 and 31' are supported on the driving shafts 33 and 33'. 34 and 34' show the barrels for winding the starting end portion of wire to be wound thereof; 35 and 35' are the end plates, having a plurality of wire catchers 36 and 36' on the

circumferential fringe; and 37 and 37' are the barrels for winding the finishing end portion of wound up wire. The barrel for winding the starting end portion of wire to be wound, the end plate and the barrel for winding the finishing end portion of wire, are fixed on each of the driving shafts 33 and 33'. 38 and 38' show the covers over the circumferential fringe of the barrel for winding the finishing end portion of wire. The covers 38 and 38' are fixed respectively on the beds 39 and 39'. As shown clearly in FIG. 13, a space (L) is formed between the said covers 38 or 38' and the corresponding end plate 35 or 35' for admitting the wire 32 therein. A plurality of projections 40 and 40' for preventing wire slip are attached on the circumferential fringe of the above barrels 34 and 34' for winding the starting end portion of wire to be wound. The wire, wound on the barrels 34 and 34', is kept by the said projections from slipping down onto the spools. 41 and 41' show catching guides movable forward and backward respectively by means of the cylinders 42 and 42'. 43 and 43' show wire position adjusting guides, movably forward and backward by means of the cylinders 44 and 44'; and 45 is a stopper fixed on the bed 39.

46 shows a traverser attached on a shifting base 47 and movable forward and backward by means of normal revolution or reversing revolution of an electric motor 48. The shifting base 47, having the said traverser installed on, is engaged with a screw rod 50, revolved by means of an electric motor 49. By revolution of the said screw rod 50, the shifting base 47 can move horizontally right and left. The shifting base 47 is supported by the supporting rods 51 on both sides of the screw rod 50, and is slideable along the supporting rods 51. 52, 53, 54, 55 and 56 show limit switches; 57 is a contactor for the limit switches 52, 53 and 54; 58 and 58' are electric motors for driving the driving shafts 33 and 33'; and 59 and 59' are wire-cutting apparatus.

The operation will be explained as follows. The spools 31 and 31' are supported by the driving shafts 33 and 33' arranged in parallel on the same plane. Now, the wire 32 is wound on the spool 31 through the traverser 46', and when a prescribed quantity of the wire 32 has been wound on the spool 31, a detecting device, such as an automatic counter, dispatches a detection signal. Receiving the said signal, the electric motor 49 is set in motion to rotate the screw rod 50, and the shifting base 47 moves, guided by the supporting rod 51, from the position 46' of the traverser to the position 46 and is stopped by the limit switch 56.

Then, by a stop signal, the cylinder 44' is set in motion to push forward the wire position adjusting guide 43'. The level of the wire is corrected between the spool 31 on which a prescribed quantity of wire has been wound and the traverser 46, and the said wire 32 is adjusted into the position where it is caught on the wire catcher 36' on the side of the empty spool 31'. The cylinders 44, 44' for the wire position adjusting guides of wire position may be connected with the cutting apparatus 59 and 59'.

When the above-mentioned limit switch 56 is set in motion, the contactor 57 of the traverser is contacted with the limit switch 52, and, firstly, the cylinder 42 is set in motion and the catching guide moves from the position 41'' to the position 41. The wire 32 is drawn toward the side of the wire catcher 36 of the spool 31 on which a prescribed quantity of wire has been wound. At this moment, the wire 32 is caught on the wire catcher 36.

At a certain time after the cylinder 42 has been set in motion, the cylinder 42' is set in motion, and the catching guide on the side of the empty spool 31' reaches from the position 41''' to the position 41'. The wire 32 is caught on the wire catcher 36', and then, cut by the wire-cutting apparatus 59'. The finishing end portion of the cut wire passes through the opening 60 of the cover and is wound on the barrel 37 inside the cover on the side of the spool 31. The finishing end portion of wire is wound in several turns on the barrel 37, and thus, a satisfactory winding operation can be assured.

It is desirable that the space (L) between the cover 38 and the end plate 35 is less than one and a half times as large as the diameter of the wire 32.

The starting end portion of wire to be wound, cut by the above-said cutting apparatus 59', remains hanging on the wire catcher 36'. At this moment, the traverser 46 is set in synchronized motion, with the action of the catching guide 41', and reversed by the action of the limit switch 54. The traverser 46 is placed above the barrel 34' for winding the starting end portion of wire to be wound, namely at the position, shown in FIG. 8 and FIG. 9. But as the said traverser is moved beyond the normal traverse limits, the starting end portion of the wire 32 is wound in several rounds on the barrel 34' and then, consecutively on the empty spool 31' through the projections 40' for preventing slip as shown in FIG. 13.

When the shifting operation has been completed in this manner, the spool on which a prescribed quantity of wire has been wound comes to rest. The catching guide, the adjusting guide of wire position and the traverser, serving also as a shifting guide, are restored to prescribed positions. In this way, the above sequence of winding operation is repeated.

According to the present invention the traverser 46 is assembled with the shifting base 47 and thus, the traverser can get nearer to the spool, and the wire can be wound smoothly. Besides, the distortion of wire can be smaller than that by the conventional shifting guide.

When the wire is shifting from the full spool 31, to the empty spool 31', the fluctuation in the track of the wire is corrected by the adjusting guides 43 and 43', so that the wire can be, without fail, caught by the wire catcher. Therefore, the wire can surely be caught without being influenced by the quantity of winding on the side of the spool 31 on which a prescribed quantity of wire has been wound, and also by the vibration of the wire 32.

According to the present invention, the barrels 34 and 34' for winding the starting end portion of wire to be wound, and the barrels 37 and 37' for winding the finishing end portion of wire surrounded with the cover for preventing the wire from swinging about, are installed so that the starting end portion and the finishing end portion of the wire are respectively wound on each of these barrels. So, it is possible to take out of the spool desired lengths of the starting end portion and the finishing end portion of wire and it is quite effective in case of connection of the wire ends and in other cases.

The covers 38 and 38' are installed around the barrels 37 and 37' so as to prevent the finishing end portion of wire on the said barrels 37 and 37' from swinging about.

It is quite effective for prevention of damage to the wire wound on the spool or of the dangerous scattering of the end portion of wire.

EXAMPLE 4: (FIG. 14 AND FIG. 15)

61 shows a wire, and the said wire 61 is wound, through a guide pulley 62 and a traverser 63 serving also as a shifting guide, on spools 65 and 65' fixed on shafts 70 and 70'. 73 and 73' show end plates contacted with outward surfaces of flanges of the spools 65 and 65', and fixed to driving shafts 71 and 71', which are integrated with the revolving shafts 70 and 70' of the spools. A plurality of wire catchers 64 and 64' are attached at regular intervals on the circumferential surface of the end plate 73, and project outside the circumferential surface of the flange of the spools 65 and 65'. 66 and 66' show wire position adjusting guides, which are drawn forward or backward by the action of cylinders 67 and 67'. The said adjusting guides 66 and 66' are placed, when they are drawn forward, as shown with a chain line in FIG. 15, at the position 66', namely, above the spools, and when they are drawn backward, as shown with a solid line, they are taken back outside of the spools. 68 shows a catching guide, placed in the middle between the spools 65 and 65'. The said catching guide can be moved forward and backward by the action of a cylinder 69. 72 and 72' show wire cutting apparatus.

The operation will be explained as follows. The wire 61 is wound through the guide pulley 62 and the traverser 63, serv-

ing also as a travelling guide, on the spool 65 fixed on the shaft 70. When a prescribed quantity of wire has been wound the shifting guide 63 moves to and stops at the position 63' in response to a shifting signal. In response to a stop signal of the shifting guide, the wire position adjusting guide 66' comes forward to the position 66'' by the action of the cylinder 67 and contacts with the wire 61' or 61'', which is strained between the traverser 63' and the spool 65, and is corrected into a position, at which the wire is most easily caught on the wire catcher 64'. 61' shows the position of the wire, when the wire 61 has been wound up to the circumferential surface of the spool 65.

Next, when the catching guide 68 is drawn back to the position 68' by the action of the cylinder 69, and at the same time, the wire 61' is pushed by the said guide so as to touch the wire catcher 64' on the side of the spool 65', the wire 61 is caught on the wire catcher 64', as the spool 65 rotates, and then, cut by the cutting apparatus 72'. After this, the wire is wound consecutively on the empty spool 65'. At the same time, the spool 65 on which a prescribed quantity of wire has been wound comes to rest. The traverser 63', serving also as a shifting guide, the adjusting guide 66'' of wire position, and the catching guide 68 are reset at prescribed positions.

As above mentioned, the present invention is characterized in that the adjusting guides 66 and 66' are provided respectively on the spools 65 and 65', and by the fact that the forward movement of the said adjusting guide, the wire, strained between the traverser and the spool, is corrected into a position so as to be caught surely on the wire catcher on the side of the empty spool, and thus, a continuous winding can be performed automatically and perfectly.

EXAMPLE 5: (FIG. 16 TO FIG. 20)

81 shows a wire, and the said wire 81 is wound through a guide pulley 82 and traversers 83, 83', serving also as a shifting guide, alternately on spools 85 and 85', respectively fixed on shafts 90 and 90'. 93 and 93' show end plates respectively, contacted with the outward surfaces of flanges of the spools 85 and 85', and respectively fixed on driving shafts 91 and 91', which are integrated with the revolving shafts 90 and 90' of the spools. A plurality of wire catchers 84 and 84' are attached at regular intervals in the peripheral direction on the circumferential surfaces of the end plates 93 and 93' and project outside the circumferential surfaces of the flanges of the spools 85 and 85'.

88 shows a catching guide, placed in the middle between the spools 85 and 85'. The said guide can be moved forward and backward by means of a cylinder 89,

86 shows a wire position adjusting guide, which is fastened onto the catching guide 88 by means of a spring washer 94 and a nut 95 at a suitable position in a vertical oblong hole 87. 92 and 92' show wire cutting apparatus.

The operation will be explained as follows. The wire 81 is wound through the guide pulley 82 and the traverser 83, serving also as a shifting guide, on the spool 85 fixed on the shaft 90. When a prescribed quantity of wire has been wound, the shifting guides 83 and 83' move to and stop at the position 83' in response to a shifting signal.

In response to a stop signal of the shifting guide, the cylinder 89 is set in motion to move the catching guide 88 to the position 88' when the adjusting guide 86 of wire position touches the wire 81' or 81'', which is strained between the traverser 83' and the spool 85. Thus, the said wire 81' is corrected into a position at which the wire can be most easily caught on the wire catcher 84'. 81'' shows the position of the wire 81, when the wire has been wound up to the circumferential surface of the spool 85.

When the catching guide 88 is drawn backward to the position 88' by the action of the cylinder 89, and at the same time, the wire 81' is pushed by the said guide so as to touch the wire catcher 84' on the side of the spool 85', the wire 81 is caught on the wire catcher 84', as the spool 85' rotates, and then, cut on the cutting apparatus 92'. After that, the wire is wound consecutively on the empty spool 85'.

At the same time, the spool 85 on which a prescribed quantity of wire has been wound comes to rest. The traverser 83', serving also as a shifting guide, and the catching guide 88 are reset at prescribed positions.

The above mentioned is an example in which one catching guide 88 and one cylinder for its movement are installed. But, when the end plate 93 is installed coaxially on the revolving shaft 91 of the spool 85, and forms a barrel for winding a prescribed length of the finishing end portion of wire on the inward side, it is necessary to install two catching guides 88'' and 88''' in order to perform this idle winding on the inward barrel. In this case, each of catching guides 88'' and 88''' may be attached with a wire position adjusting guide 86.

The wire position adjusting guide 86 on the catching guide 88 is curved upwardly toward its end so as to adjust the wire position up and down. It is necessary that the length (l) of the curved part of the adjusting guide 86 should be determined corresponding to the quantity of wire wound on the spool.

EXAMPLE 6: (FIG. 21 TO FIG. 23)

101 and 101' show spools for winding a wire 102, and the spools 101 and 101' are supported respectively on driving shafts 103 and 103'. 104 and 104' show barrels for winding the starting end portion of wire to be wound; 105 and 105' show end plates having many wire catchers 106 and 106' at regular intervals in the circumferential direction on the periphery; and 107 and 107' show barrels for winding the finishing end portion of wire. The barrel for winding the starting end portion of wire to be wound, the end plate and the barrel for winding the finishing end portion of wire are fixed on each of the driving shafts 103 and 103'. 108 and 108' show covers over the barrels for winding the finishing end portion of wire. A space is formed between the said cover 108 or 108' and the corresponding end plate 105 or 105' for admitting the wire 102 therein and the said covers are respectively fixed on the beds 109 and 109'.

Many projections 110 and 110' for preventing wire slip are attached to the side of each spool, at similar intervals in the circumferential direction on the circumferential fringe of the above-said barrels 104 and 104' for winding the starting end portion of wire to be wound. The wire wound on the barrels 104 and 104' is prevented by the said projections 110 and 110' from slipping down onto the spools. 111 and 111' show catching guides, movable forward and backward by means of the cylinders 112 and 112'; 113 and 113' show adjusting guides, respectively movable forward and backward by means of the cylinders 114 and 114'. 116 shows the traverser put on the shifting base 117. The said traverser is moved back and forth by a normal or reversing revolution of the electric motor 118, while the shifting base 117 is engaged with the screwed rod 120, which rotates by means of the electric motor 119. And by the rotation of the said screwed rod 120, the shifting base 117 can move horizontally right and left. The shifting base 117 is supported on the supporting rods 121 and 121 on both sides of the screwed rod 120, and can slide along the supporting rods 121 and 121. 115 shows a stopper (an adjusting guide of wire position); 122 is a central safety screen fixed on a slider 124 which is engaged slidably with the bed 123. The stopped 115 and the screen 122 can slide together on the bed 123 by the action of the cylinder 125.

126 and 126' show screens which are installed on the shifting base 117 for protection of the traverser 116 and for isolating both spools from each other more perfectly.

When the wire is wound on either of the spools 101 and 101', the above-said stopper and screens are placed respectively in the positions 115' and 122' as shown in FIG. 23 and intercept both the spools 101 and 101'.

At that time, supposing the wire is wound on the spool 101, the traverser is placed in the position 116 so that the screen 70 126' is just aligned with the screen 122.

Then, when the spool 101 becomes full and the wire 102 is shafted to the other spool 101', the electric motor starts according to a suitable signal and the screwed rod 120 begins to rotate thereby. The shifting base 117 moves by the guidance 75

of the supporting rod 121, and the traverser moves from the position 116 to the position 116'.

The cylinder 114' is set in motion to push out the adjusting guide 113'. The level of the wire is corrected between the spool 101 and the traverser 116' so that the wire 102 is caught on the wire catcher 106' of the empty spool 101'.

The catching guide travels by the action of the cylinder from the position 111'' to the position 111 to draw the wire 102 toward the wire catcher 106 of the spool 101 on which a prescribed quantity of wire has been wound. At that time, the wire 102 is caught on the wire catcher 106 to be wound on the barrel 107 for winding the finishing end portion of wire. After a certain time, the catching guide on the side of the empty spool 101' moves from the position 111''' to the position 111'''' by the action of the cylinder, and the wire 102 is caught on the wire catcher 106' to be cut on the wire-cutting apparatus 127'. The finishing end portion of the cut wire passes through the opening of the cover of the barrel for winding the finishing end portion of wire on the side of the spool 101 to be wound on the barrel inside the cover. Thus a perfect wire winding can be attained.

The starting end portion of wire, which has been cut on the above-said cutting apparatus 127', remains hanging on the wire catcher 106'. Now, the starting end portion of the wire 102 is wound in several turns on the barrel 104', and then passes through the projections 110' for preventing wire slip onto the empty spool 101'.

When the above-mentioned shifting has been completed in this manner, the spool on which a prescribed quantity of wire has been wound comes to rest. The catching guide, the wire position adjusting guide and the traverser serving also as a travelling guide are restored to prescribed positions. In this way, the above sequence of winding operations is repeated.

When the wire is shifted as above by the action of the cylinder 125, the stopper and the screen are drawn back respectively at the positions 115 and 122. When the stopper is placed at the position 115 and the catching guide comes to the position 111, the wire 102 is caught on the wire catcher 106 of the spool 101 on which a prescribed quantity of wire has been wound, but is not caught with the wire catcher 106' of the empty spool 101'. Thus, in a certain period, while the catching guide moves from 111''' to 111' on the side of the empty spool, the wire 102 can be wound on the barrel 107 for winding the finishing end portion of wire. After the period, the wire is caught on the wire catcher 106' on the empty spool. Thus, the operation of shifting is completed.

What is claimed is:

1. In a continuous wire winding apparatus including two or more spools onto which said wire is to be wound, means to rotate said spools, means positioned to lead said wire onto a first of said spools, and traversing guide means positioned with respect to said spools to selectively guide said wire onto a second of said spools when a prescribed amount of wire has been wound on said first spool; the improvement comprising a first plurality of electrodes and a second plurality of electrodes positioned between said first and second spools said first plurality of electrodes being adjacent said first spool and said second plurality of electrodes being adjacent said second spool; a plurality of wire catchers mounted adjacent the peripheries of said first and second spools adjacent said first and second pluralities of electrodes, respectively, said wire catchers of said second spool adapted to catch said wire when said traversing guide means is traversed to guide said wire onto said second spool; means attached to said pluralities of electrodes to selectively move said second plurality of electrodes into a position to be contacted by said wire when said wire is caught by said wire catchers of said second spool, but to maintain said first plurality of electrodes in a position removed from said wire; and current supply means attached to said pluralities of electrodes for completing a circuit and heating said wire when said wire contacts said electrodes, whereby said wire is severed.

2. The improvement claimed in claim 1, further comprising first barrel means mounted on each of said spools for winding the starting end portion of said wire when said wire is initially wound on each of said spools; an end plate mounted on each of said spools outwardly of said first barrel means, said wire catchers being positioned on said end plates; second barrel means mounted on each of said spools outwardly of said end plates for winding the finishing end portion of said wire on said spools when said wire has been transferred to another of said spools; cover means covering each of said second barrel means for preventing said finishing end portion from randomly swinging; at least one catching guide movably positioned between said spools for adjusting the vertical position of said wire after the traversing movement of said traversing guide means; and at least one wire position adjusting guide mounted between said spools for selectively moving said wire toward said wire catchers of said second spool after said traversing movement of said traversing guide means.

3. The improvement claimed in claim 2, wherein said adjusting guide is movably mounted so as to guide said wire to a position to be caught by said wire catchers of said second spool.

5 4. The improvement claimed in claim 2, wherein said adjusting guide is attached to said catching guide in such a manner that the level of said adjusting guide is adjustable.

10 5. The improvement claimed in claim 2, further comprising a screen positioned between said first and second spools and serving as a stopper between said spools, said screen being movable from between said spools when said wire is shifted and operable as a wire guide to wind said finishing end portion of said wire.

15 6. The improvement claimed in claim 5, further comprising screen means mounted on each side of said traversing guide means for aligning with said screen when said screen is advanced between the spools when the wire is wound.
